UNITED STATES PATENT OFFICE.

THOMAS SPENCER MILLER, OF SOUTH ORANGE, AND JOSEPH H. DICKINSON, OF MONTCLAIR, NEW JERSEY.

PORTABLE DERRICK.

No. 890,158.

Specification of Letters Patent.

Patented June 9, 1908.

Application filed November 14, 1903. Serial No. 181,204.

To all whom it may concern:

Be it known that we, THOMAS SPENCER MILLER, a citizen of the United States, and a resident of South Orange, county of Essex, and State of New Jersey, and JOSEPH H. DICKINSON, a citizen of the United States, and a resident of Montclair, county of Essex, and State of New Jersey, have invented a new and useful Improvement in Portable Derricks, of which the following is a specification.

Our present invention relates to that class of derricks principally employed in logging in which the derrick is mounted upon a platform that may be either supported upon a flat car beneath it or by an independent support permitting the flat cars to pass beneath it. Said independent support has sometimes consisted, as shown in our Patent No. 726325, substantially of legs supporting the derrick platform from the ends of the ties on opposite sides of the railway track or, as shown in the Baptist patent No. 662906, of a supplemental track section of greater gage than the railway track.

Our present invention is applicable to a derrick supported by either of these forms of independent support.

In our application No. 169862 filed August 30 18, 1903, we have shown the derrick platform when carried by the car beneath it as provided with an operative engagement between the engine on the platform and the wheel or wheels of the car, so that said engine can act as its own locomotive. In the use of the apparatus described in said application, whenever the derrick platform was set upon its independent supports for operation, it was necessary that the supporting or 35 locomotive car should be run to a sufficient distance on the track to be out of the way of the other cars as they passed to, under and from the derrick in being loaded.

The object of our present invention is to provide means whereby said supporting or locomotive car when not in use for supporting or carrying the derrick can be disposed of adjacent to the derrick so as to be near at hand for use whenever required and in such manner as not to obstruct the track for the passage of other cars.

In the accompanying drawings, Figure 1 represents in plan view a car supplied with a traction mechanism and therefore adapted to perform the function of the sup-

porting car described in our said application No. 169862. Fig. 2 shows in side view said car in position for supporting the derrick platform with its traction mechanism in operative connection with the derrick mechanism. Fig. 3 represents said derrick as set upon its independent supports, and said car in full lines as adjacent thereto on the track. In dotted lines it represents said car as disposed in the manner in which we prefer according to our invention. Fig. 4 is a detail. Figs. 5 and 6 are front views partly in section to show the operation of the supports for the platform upon the car, in two positions.

1 is the railway track. 2 are the ties 70 thereof.

3 is the derrick platform. 4, the derrick-boom projecting from one end thereof. 5 is the rope-drum operating the hoisting-rope 6. 7 is a rope-drum operating the spotting-rope 75 8 whereby the cars are drawn as required under the platform or into loading position. 9 is a gear, 10 is the boiler mounted on said platform wherefrom all of said parts are driven by a suitable engine and connections 80 mounted on said platform. 11 are the supports whereby said platform is supported independently of said cars on opposite sides of the track and at such an elevation above the track as to permit of the free passage of the 85 cars underneath.

12 are supports between the derrick platform and the car platform onto which the support of the derrick platform may be transferred from the supports 11. A mechanism whereby these supports 12 may be operated is shown in detail in Figs. 5 and 6, wherein each pair of said supports 12 is coupled to a pair of levers 13 operated by a piston-rod 14 from a steam or hydraulic cylinder 15 so that the supports 12 may be forced downward until the mechanism on the derrick platform raises itself and the platform upon the car in the position shown in Figs. 2 and 6.

16 is the car-frame. 17 are the axles thereof to each of which is fixed a sprocket-wheel 18 connected, respectively, by the sprocket chains 19 with the sprockets 20 fixed to the shaft 21 to which is also fixed the spur-wheel 22 adapted to engage with the spur-wheel 9 already referred to. The shaft 21 has its bearings in a rocker-frame 23 fulcrumed on one of the car axles and counterbalanced by an adjustable weight 24.

100

105

110

25 is a latch secured to the car-frame whereby the rocker-frame 23 may be held in the position shown in Fig. 2 for engagement between the spur-wheels 9 and 22. By the 5 release of said latch the rocker-frame falls into the position shown in Fig. 3 so that the presence of the traction mechanism on the car does not interfere with its use for any purpose that may be required or with the 10 running of it to any point that may be desired. 26 are cross-beams secured to the top of the car-frame. 27 are eyes projecting above the said car beams.

To the rear of the derrick platform is pivoted 15 a frame 28 consisting of two parallel booms secured together and capable of being moved from the horizontal position shown in full lines, Fig. 3, to the vertical position shown in dotted lines by the boom-hoisting-rope 29 which passes over the elevated 20 sheave 30 around the sheave 31 and is coiled upon the winch-head 32, shown in Figs. 3 and 6. Projecting from the under side of the boom-frame 28 are hooks 33 so positioned 25 that when the boom-frame is lowered each of them will enter one of the eyes 27 as the car is moved out from under the derrick platform. Each of these hooks is guarded by a latch 34 serving to retain the eyes within the hooks 30 when the boom-frame 28 is hoisted in vertical position. The boom-hoisting-rope 29 may be passed around the sheave 35 and made fast to the car-frame at 36 so as to be adapted 35 for hauling the car into a position beneath the boom from under the platform, thence to be hoisted up with the boom into the position shown in dotted lines by the further in-haul of the rope 29. When in the latter 40 position, the boom is held as long as required by a latch 37.

It will be observed that under our present improvement, the supporting or traction-car instead of being disposed of at a distance on the trackway, as in our application 45 No. 169862, is disposed of by being lifted bodily from the track. We do not wish to be understood as limiting ourselves to the manner in which this is accomplished although we prefer to accomplish it in the manner above described because we thereby lift the car in such position as to substantially 50 register with the track upon being lowered and, also, in such position that it acts as a counterbalance to the weights being handled 55 by the boom 4 of the derrick.

Although in the above description the car that is described as being raised bodily from the track is the supporting or traction car we, nevertheless, do not wish to limit ourselves in that regard because the same principle may be employed to temporarily get rid of a car where the next car behind it is the one required for the load.

In our co-pending application No. 181,714, 60 we have shown lifting mechanism interposed

between the derrick frame and the car, whereby said derrick frame may be mounted upon the car. The mechanism employed in said co-pending application is similar to that herein shown and in such case certain claims 70 have been made to this form.

Having thus described our invention, we claim as new and desire to secure by Letters Patent:—

1. A derrick provided with supports permitting of the passage of cars beneath its platform, and having its boom projecting from one end of said platform, in combination with a boom projecting from the opposite end of said platform whereby a car may 80 be lifted bodily in such position as to counterbalance the loads handled by said derrick.

2. In combination, a derrick, a car free to move relatively to said derrick along a railway track beneath the same, supports for said derrick not obstructing said movement of said car and mechanism whereby the car may be raised bodily to permit of the passage of other cars beneath said derrick.

3. In combination, a derrick and its engine, a car free to move relatively to said derrick and engine along a railway track beneath the same, supports for said derrick and engine not obstructing said movement of said car, mechanism whereby said car may be raised bodily to permit of the passage of other cars beneath said derrick and engine.

4. In combination, a derrick, a car free to move relatively to said derrick along a railway track beneath the same, supports for said derrick not obstructing said movement of said car, mechanism interposed between said derrick and said car whereby said derrick is raised upon said car and mechanism whereby said car may be raised bodily to permit of the passage of other cars under said derrick.

5. In combination, a derrick, a car free to move relatively to said derrick along a railway track beneath the same, supports for said derrick not obstructing said movements of said car, a traction mechanism on said car, a motor mounted upon the derrick and adapted to be connected with said traction mechanism and mechanism whereby said car may be raised bodily to permit of the passage of other cars under said derrick.

6. In combination, a hoisting apparatus, supports for the same adapted to straddle a car, a car free to move relatively to said hoisting apparatus along a railway track beneath the same, hoisting apparatus, raising and propelling mechanism and car raising mechanism, all coacting with said car.

7. In combination, a hoisting apparatus, supports for the same adapted to straddle a car, a car free to move relatively to said hoisting apparatus along a railway track beneath the same, hoisting apparatus raising

- mechanism, car raising mechanism both co-acting with said car.
8. In combination, a hoisting apparatus and its hoisting engine, a car movable independently of the same along a railway track beneath the same and means whereby said car may be raised bodily beside said engine.
9. In combination, a car, a track along which the car is adapted to travel, a hoisting apparatus and its engine adapted to straddle said car and means whereby said car may be raised bodily and independently of said engine to permit of the passage of other cars along said track.
10. In combination, a car, a traction mechanism on said car, a hoisting apparatus and its engine adapted to straddle said car, an operative connection between said traction mechanism and said engine, means for disconnecting the same to permit said car to be moved upon the track independently of said engine and means whereby said car may be raised bodily to permit of the passage of other cars beneath said engine.
11. In combination, a car, a platform secured to supports straddling said car, an engine and hoisting mechanism mounted upon said platform, mechanism whereby said platform may be raised so as to be supported by said car and mechanism whereby said car may be raised so as to be supported by said platform.
12. In combination, a platform, a hoisting apparatus and hoisting engine upon said platform, a car lifting mechanism at one side of said platform and supports for said platform leaving a passage-way for cars beneath the same.
13. In combination, a platform, supports for the same leaving a passage-way for cars beneath the same, a hoist and its engine on said platform, jacking mechanism extending from said platform downward into the car passage-way beneath the same, a traction driver adapted to engage with traction mechanism on the car beneath the same and a car lifting mechanism.
14. In combination, a hoist frame, a hoist engine mounted interiorly at an elevation on said frame and car lifting mechanism mounted exteriorly on said frame.
15. The combination of a frame, hoisting and conveying apparatus carried thereby, a propelling or traction mechanism embodying a car, and a car-carrying frame to which said car is adapted to be detachably connected, said car carrying frame being movably secured to the hoisting and conveying apparatus frame.
16. The combination of a frame, hoisting apparatus carried thereby, a supplemental frame pivoted to the first-mentioned frame, means for swinging said supplemental frame on its pivots, traction mechanism, and means for detachably securing the traction mech-
- anism to said supplemental frame to enable such mechanism to be raised and lowered.
17. The combination of a frame, an engine carried thereby, a second frame movably connected to the first-mentioned frame, traction mechanism, means for detachably securing the traction mechanism to the second frame, and means connected to said frame and operated by the engine for lifting the second mentioned frame and the propelling mechanism.
18. The combination of a frame, hoisting apparatus carried thereby, a second frame movably connected to the first mentioned frame, propelling means, including a car or truck, means for connecting the latter to said second frame when such frame occupies an approximately horizontal position, and means for swinging said frame and the car or truck out of such approximately horizontal position into an approximately vertical position.
19. The combination of a frame, hoisting apparatus carried thereby, a second car-carrying frame secured to the first mentioned frame, means for swinging the second frame from an approximately horizontal position to an approximately vertical position alongside the first mentioned frame, and means for locking the second frame in its vertical position.
20. In a log loader the combination of a frame, a hoisting apparatus carried thereby, a swinging frame carried by the first mentioned frame, and a propelling or traction car detachably carried by the swinging frame.
21. The combination of a frame, hoisting apparatus carried thereby, a car adapted to be moved beneath said frame and connected therewith to transport such frame, a supplemental frame carried by the first mentioned frame, means for connecting the car to the supplemental frame when such car is not in use for transporting the structure, and means for moving such supplemental frame and car to permit the passage of other cars through the first mentioned frame.
22. In a log loader, the combination with a structure having a platform or base, beneath which cars may pass and upon any of which cars the structure is adapted to rest, of propelling means connected with a platform and provided with traction wheels adapted to engage the track when in use, and to be raised upon the plane of the top surface of the platform when not in use.
23. In a log loader, the combination of a frame beneath which cars may pass and upon any of which cars the platform is adapted to rest, of propelling means connected with the platform and provided with traction devices adapted to engage the track when in use.
24. In a log loader, the combination with a platform or base beneath which cars may pass and upon any of which cars the plat-

form may be supported, an engine, a swinging truck connected to the platform and adapted to be swung from a position in engagement with the track to a position upon 5 the plane of the top surface of the platform, and vice versa, a power-transmitting means between the engine and truck.

25. In a log loader, the combination of a frame constructed to permit the passage of a 10 car or cars therebeneath, and upon which car or cars the platform is adapted to be supported, and propelling means connected to said platform and embodying a swinging truck provided with traction wheels, said 15 truck being so arranged as to allow its wheels to operatively engage such track and to be swung into inoperative position above the base.

26. In a log loader, a structure comprising 20 a frame-work having a platform, such frame-work being adapted to permit the passage of a car or cars therebeneath, and upon which car or cars the frame-work is adapted to rest, a propelling means provided with traction 25 wheels adapted to engage the track, and to be raised above the frame of the top surface of the platform.

27. In a log-loading machine, the combination with a track adapted to have a train 30 of cars movable thereon, of a log loader constructed to permit the train of cars to move therebeneath, and upon any of which cars

the loader is adapted to be supported, and means for propelling said loader, such means comprising a swinging truck adapted to occasionally engage such track and to operatively connect it with the engine of the log 35 loader.

28. The combination with a log-loading machine constructed to permit the passage 40 of cars therebeneath and upon which cars the machine is adapted to be supported; means for propelling such machine, such means comprising a truck-frame pivoted upon a transverse axis of the base frame of 45 the loader, and carrying a pair of wheels adapted to engage such track, cables operated by the engine of such log-loading machine and adapted to swing such truck frame upon its axis, and driving means operated by 50 such engine and adapted to rotate such wheels.
